INSECT ELECTROCUTOR

Herbert J. Bowman, South Bend, Ind.

Application May 28, 1932, Serial No. 614,224

14 Claims. (Cl. 43—112)

The invention relates to insect electrocutors, and particularly to a device of this character for electrocuting insects and collecting them after being electrocuted.

5 The principle object of the invention is to provide a device of this character comprising a casing having an opening therein across which oppositely charged electrodes extend and beneath which is positioned a drawer into which insects 10 which are electrocuted when passing through said opening will fall.

A further object is to provide a device of this character including a casing having an opening and a plurality of electrodes preassembled in a 15 unit for installation in the opening of said casing.

A further object is to provide a device of this character including a casing and an electrode assembly and resilient means carried by said casing for securing said electrode assembly in 20 said casing in operative position.

A further object is to provide a device of this character having an electrode assembly including two sets of interconnected parallel electrodes positioned in alternating relation and carried by 25 a pair of spaced parallel bars.

A further object is to provide simple means for interconnecting a pair of telescoping sets of electrodes with a source of power.

A further object is to provide a device of this 30 character which is simple to construct and assemble, and cheap to manufacture.

With the above and other objects in view, the invention resides in the combination and arrangement of parts as hereinafter set forth, 35 shown in the drawing, described and claimed, it being understood that changes in the precise embodiment of the invention may be made within the scope of what is claimed without departing from the spirit of the invention.

40 In the drawing:

Figure 1 is a perspective view of the device.

Figure 2 is a top plan view of the electrode assembly.

Figure 3 is a fragmentary longitudinal vertical 45 sectional view of the device illustrating the manner in which the electrode assembly is secured to the casing.

Figure 4 is a fragmentary perspective view of the supporting bars of the electrode assembly.

50 Figure 5 is a perspective view of the spring member securing said electrode assembly to said casing.

Referring to the drawing, which illustrates the 55 preferred embodiment of the invention, the numeral 10 designates a casing comprising a bottom

11, sides 12, and ends 13. Said sides and ends have inwardly directed flanges 14 projecting from the upper edges thereof. A cover plate 15 is suitably secured to flanges 14 at one end thereof to form a closed compartment at one end of the 60 casing for purposes to be hereinafter set forth, and leaving the major portion of the casing open at its top. An opening 16 is formed in one end 13 of the casing for the reception of a sliding drawer 17 extending into said casing beneath said top 65 opening and being of a dimension slightly greater than the dimension of the opening in the top of the casing.

An electrode grill is carried by the casing to extend across the top opening thereof and comprises a plurality of spaced parallel rods or electrodes 18 interconnected at one of their ends by a contact member 20, and a second set of spaced parallel electrodes 19 interconnected at one of their ends by contact member 21. The electrodes 75 18 and 19 of each set are equally spaced apart. A pair of insulating bars 22, each having a plurality of aligned openings 23 therethrough, which openings are spaced apart a distance equal to one half the spacing between electrodes 18 and 80 19 of their respective sets, form means for mounting the sets of electrodes to form a grill. The sets of electrodes are positioned in alternating relation, with electrodes of opposite sets passing through adjacent openings 23 in the bars 22, 85 and the contact members 20 and 21 positioned at opposite ends of the assembly as illustrated in Figure 2. The bars 22 are of substantially L-shape to provide a recess at the lower rear side thereof, and when the grill is assembled in 90 operative relation with the bars 22 at the opposite ends thereof, the contact members 20 and 21 are positioned in said recess and the free ends of the electrodes of the opposite set are spaced from said contact members, as illustrated in Figure 4. Flanges 24 are formed at the opposite 95 ends of bars 22 and said flanges are provided with a lower concaved surface at 25.

At the opposite sides of the opening in the top of the casing, and spaced below the flanges 14 of the casing a distance substantially equal to the thickness of the bars 22, electrode grill supporting members are carried by the side walls 100 12 of the casing. These supporting members comprise a plate 26 spot welded to the side walls 105 12 and supporting a horizontal inwardly directed plate 27 which terminates in a convexed end portion 28 which is preferably formed of sheet metal.

In assembling the device, the electrode grill 110

having first been preassembled, said grill is inserted into the casing through the drawer opening 16 thereof. The grill is then positioned immediately below the top opening of the casing 5 with the bars 22, which are of a length substantially equal to the width of the casing, positioned inwardly of the end of the grill and between the plate 27 of the supporting members and the flanges 14 of the casing. The bars are 10 then slid on the electrodes towards the ends of the grill and between said members to bring the concaved portion 25 of the end portion 24 thereof into engagement with the convex spring members 28, whereby said spring members will securely hold and lock said bars in operative relation to the casing by pressing them against the flanges 14. When the bars 22 have been thus 15 properly mounted and locked in the casing 10 and the two sets of electrodes 18, 19 have been 20 operatively positioned relative to each other and to the bars 22, sealing wax or other suitable adhesive material may be applied to the lower recessed portion of bars 22 to hold the electrodes 18, 19 and their contact members 20, 21 in operative 25 fixed relation relative to the bars whereby they are prevented from relative movement into contact with each other to close the circuit which will be hereinafter described.

A conventional electric transformer 29 is 30 mounted in the casing 10 at the end thereof enclosed by cover plate 15, and has connection with a suitable source of power by means of lead 30. The outer electrode of the set of electrodes 18 is elongated at 31 to extend past the contact 35 member 21 of the other set, and one of the electrodes of the set of electrodes 19 extends rearwardly from contact member 21 at 32, and these two contact extensions 31 and 32 are connected to the opposite ends of one of the coils of the 40 transformer 29, whereby the electrodes of the sets 18 and 19 are operatively connected to the transformer to be oppositely charged.

The spaced alternate electrodes of the opposite sets form parts of a normally open circuit. Then, 45 if the transformer is energized, and an insect passes between the spaced electrodes, the body of the insect forms a conductor to close the circuit between the electrodes and the charge passes through the body of the insect to electrocute it, 50 whereupon it drops into the drawer 17. If, as sometimes occurs with these devices, the insect has only been singed rather than killed, and it is still alive after it has fallen into the drawer, it cannot escape without again passing between 55 the electrodes. The second charge of electricity is certain to kill the insect. The sliding drawer permits ready removal of the electrocuted insects from the device, and the ready replacement of a lure, such as honey or the like, by which the 60 insects may be drawn to the device.

The invention having been set forth, what is claimed as new and useful is:

1. In combination, a casing having an opening 65 therein, a transformer mounted in said casing in spaced relation to said opening, a sliding drawer mounted in said casing and positioned beneath said opening, a plurality of spaced electrodes extending across said opening, insulating bars positioned at opposite ends of said opening and supporting the ends of said electrodes, a pair of 70 spring members carried by said casing adjacent each end of said opening, said spring members operatively mounting said bars relative to said opening, means interconnecting alternate electrodes to form two sets of electrodes, and means

interconnecting each set of electrodes with the transformer.

2. In combination, a casing having an opening 80 therein, a sliding drawer mounted in said casing and positioned beneath said opening, a plurality of spaced electrodes extending across said opening, insulating bars positioned at opposite ends of said opening and supporting the ends of said electrodes, a pair of spring members carried by said casing adjacent each end of said opening, said spring members operatively mounting said bars in said casing relative to said opening, means interconnecting alternate electrodes to form two sets of electrodes, and means connecting each set of electrodes with opposite terminals of an 85 electric circuit.

3. In combination, a casing having an opening 90 therein, a plurality of spaced electrodes extending across said opening, insulating bars positioned at opposite ends of said opening and supporting the ends of said electrodes, a pair of spring members carried by said casing adjacent each end of said opening to secure said bars in said casing, means interconnecting alternate electrodes to form two sets of electrodes, and means 95 connecting each set of electrodes with opposite terminals of an electric circuit.

4. In combination, an open-ended casing having 100 marginal inwardly directed flanges at the open end thereof, a plurality of spaced electrodes 105 extending across said opening, insulating bars positioned at opposite ends of said opening and supporting said electrodes, resilient means carried by said casing in spaced relation to said flanges at the ends of said opening, said bars 110 being constrictively held between said flanges and resilient means, means interconnecting alternate electrodes to form two sets of electrodes, and means connecting each set of electrodes with opposite terminals of an electric circuit.

5. In combination, an open-ended casing having 115 marginal inwardly directed flanges at the open end thereof, an insulating bar adjacent said opening, resilient means carried by said casing in spaced relation to said flanges, said resilient 120 means pressing said bar into engagement with said flange, and a plurality of spaced electrically charged members extending across said opening and supported by said insulating bar.

6. In combination, a casing having an opening 125 therein, resilient means carried by said casing adjacent said opening, insulating bars positioned by said resilient means adjacent said opening in a position to close a portion of said opening at opposite ends thereof, and a plurality of spaced electrically charged members 130 extending across said opening and supported by said insulating bars, said bars and members being disposed within the outline of said casing.

7. In combination, a casing having an opening 135 in one of its sides spaced from one edge thereof, a supporting member carried by said casing in spaced relation to said opening, an insulating bar interposed between said supporting member and the side of said casing having the opening 140 therein, and a plurality of spaced electrically charged members extending across said opening and supported by said insulating bar.

8. In combination, an open-ended casing having 145 a marginal flange extending inwardly from the upper end thereof, convex resilient members carried by said casing in spaced relation to said flange, insulating bars having a concavity formed in one face thereof, said insulating bars being interposed between said resilient members and 150

- 5 said flange with said convex members seated in the concavity of said bars, and a plurality of spaced electrically charged members extending across said opening and supported by said insulating bars.
9. In combination, an open-ended casing having a marginal inwardly directed flange at the open end thereof, a supporting member carried by said casing and positioned in spaced relation to said flange, a convex resilient member carried by said supporting member, an insulating bar having a concavity formed in one face thereof, said insulating bar being interpositioned between said supporting member and said flange with said resilient member seated in the concavity thereof, and a plurality of spaced electrically charged members carried by said bar and spanning said opening. 80
10. In combination, a casing having an opening therein, a plurality of spaced electrically charged members spanning said opening, insulating members mounting said last named members, and resilient means carried by said casing constrictively engaging said insulating member to mount said member within said casing. 85
15. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 90
20. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 95
25. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 100
30. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 105
35. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 110
40. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 115
45. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 120
50. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 125
55. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 130
60. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 135
65. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 140
70. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 145
75. In combination, a casing having an opening therein, a pair of insulating members carried by said casing adjacent said opening and each having a plurality of apertures therein, a plurality of electrodes mounted in said apertures, means interconnecting alternate electrodes to form two sets of electrodes, and means connecting said sets of electrodes with opposite terminals of an electric circuit. 150
